CLOSURE MEANS FOR TUBES AND THE
LIKEIngwald Martinus Evensen, Weston, Ontario,
Canada

Application March 11, 1937, Serial No. 130,260

2 Claims. (Cl. 221—60)

The invention relates to improvements in closure means for tubes and the like, as described in the present specification and illustrated in the accompanying drawing that forms a part of the same.

The invention consists essentially of the novel features of construction pointed out broadly and specifically in the claims for novelty following a description in detail of an acceptable form of the invention.

The objects of the invention are to devise a closure means for tubes and other containers for retaining liquids and semi-liquids as well as other matters of a similar nature, e. g., tooth-pastes, oil tubes, vaselines, shaving creams and innumerable other commercial articles; to facilitate matters for the consumer in enabling him to remove the contents from the tube without getting his fingers smeared, which so often occurs in the use of ordinary capped tubes; to insure a tight closure for the tube and the consequent saving of the contents thereof; to eliminate the constant irritation and annoyance caused by the frequent losses of the caps of the tubes, and there-
fore to substitute a cap that will be a fixed part of the tube itself and at the same time can not only be easily raised or lowered but securely locked in its closed position; to materially reduce the loss of the tube contents owing to the fact that by using this particular closure the unused contents of the tubes that may still project beyond the neck of the tube will be forced back into the tube rather than therearound, when the closure is closed; and generally to provide a very serviceable, durable and efficient closure means at the minimum cost, that may be used for many varied purposes.

In the drawing:

Figure 1 is a perspective fragmentary view of the tube without the closure means.

Figure 2 is a perspective fragmentary view of the tube with the closure means mounted thereon.

Figure 3 is an assembly view of the different parts of the closure shown in perspective.

Figure 4 is an enlarged fragmentary sectional view of the tube with the closure means mounted thereon.

Figure 5 is an enlarged fragmentary sectional view of the tube and closure means in right angle to the view shown in Figure 4.

Like numerals of reference indicate corresponding parts in the various figures.

Referring to the drawings, the closure means is in the form of a cap as indicated by the numeral 10 having the lid 11 and the hinge bearing 12

and the central projecting curved boss 13 and the finger grip 14.

The lid 11 is pivotally secured to the cap 10 by the hinged pin 20. The curved boss 13 fits into the cap 10 and into the tube 15 when the lid 11 is turned down on the cap. The cap 10 has the orifice or groove 16 and the smooth vertical surface 17 which is engaged by the finger grip 14, when the lid is brought down on the cap. At the same time the spring 18 is pressed down into the orifice or groove 16. The cap is internally threaded for engagement with the externally threaded neck 19 of the tube 21. The cap 10 has the groove 22 adapted to receive the spring 18 when the cap is locked to the tube.

All that is necessary is to turn the cap on the neck of the tube until the spring 18 engages the recess 22. The curved part of the spring 18 follows the threads on the neck of the tube, and this spring is consequently forced into the recess 22, thereby locking the cap to the tube.

For unlocking the closure means, the cap is simply turned back to its original position, the spring 18 will then return to the smooth vertical surface 23, on the neck 24 of the tube 21, and by pressing the finger grip 14 upwardly the lid can be raised.

In other words, it is the turning of the cap on the neck of the tube that locks and unlocks the lid and consequently the cap to the tube. The curved boss 13 fits tightly into the neck of the tube and prevents the escape of the contents of the tube during the operation and at the same time it prevents the contents from becoming hardened due to exposure to the air.

It will be seen that it is not necessary to remove the cap from the container, the turning of the cap on the neck of the tube will allow the free use of the contents of the tube when desired.

It is of course understood that the closure means herein described may be formed with slight modifications for other purposes apart from tubes, such as cans, pipefittings, bottles, radiator caps on automobiles, and on innumerable other objects, without departing from the scope of this invention.

What I claim is:

1. In closure means for tubes and the like, a container having a tubular seat member externally threaded and having a vertical smooth surface breaking the threads, an internally threaded cap having a vertical groove on its inner side and engaging with the tubular seat member of said container, a lid hingedly secured to said cap, and a spring secured to said lid and having a tongue 50

and adapted to fit between the tubular member and the cap and to engage with the groove of the cap in the closed position of the lid.

2. In closure means for tubes and the like, a container having a tubular seat member externally threaded and having a smooth surface breaking the threads, an internally threaded cap having a vertical groove on its inner side and engaging with the tubular seat member of said con-

tainer, a lid hingedly secured to said cap and having a central projecting curved boss, a finger grip projecting from said lid, and a spring secured to said lid and having a tongue and adapted to fit between the tubular member and the cap and to engage with the groove of the cap in the closed position of the lid. 5

INGWALD MARTINIUS EVENSEN.
